UNITED STATES PATENT OFFICE

147,881

DESIGN FOR A ROADSIDE SHOP OR THE LIKE

Arthur H. Valentine, Wichita, Kans., assignor to Valentine Industries, Inc., Wichita, Kans., a corporation of Kansas

Application May 13, 1946, Serial No. 129,667

Term of patent 3½ years

(Cl. D13—1)

To all whom it may concern:

Be it known that I, Arthur H. Valentine, a citizen of the United States and a resident of the city of Wichita, in the county of Sedgwick and State of Kansas, have invented a new, original, and ornamental Design for a Roadside Shop or the like, of which the following is a specification, reference being had to the accompanying drawing, forming a part thereof.

On the drawing:

structure of Figure 1, or a view taken from the left-hand side of Figure 2.

I claim:

The ornamental design for a roadside shop or the like, substantially as shown.

ARTHUR H. VALENTINE.
